[57] CLAIM

The ornamental design for a combined woodworking router and shaper machine, substantially as shown and described.

DESCRIPTION

FIG. 1 is a front perspective view of a combined woodworking router and shaper machine showing my new design;

FIG. 2 is a rear perspective view of FIG. 1;

FIG. 3 is a front perspective view of a second embodiment of my design; and

FIG. 4 is a rear perspective view of FIG. 3.

FIG-1

FIG-2

FIG-3FIG-4
